Patented Apr. 5, 1921.

FIG. 1

FIG. 4.

FIG. 2

INVENTOR

Albert H. Neller,
BY
William Louden,
ATTORNEY

UNITED STATES PATENT OFFICE.

ALBERT H. NELLER, OF FAIRFIELD, IOWA, ASSIGNOR TO LOUDEN MACHINERY COMPANY, OF FAIRFIELD, IOWA, A CORPORATION OF IOWA.

SWILL-DISTRIBUTER.

1,373,521.

Specification of Letters Patent.

Patented Apr. 5, 1921.

Application filed November 28, 1919. Serial No. 341,190.

To all whom it may concern:

Be it known that I, ALBERT H. NELLER, a citizen of the United States, residing at Fairfield, in the county of Jefferson and State of Iowa, have invented a new and useful Improvement in Swill-Distributors, of which the following is a specification.

My invention relates to a container for swill and other liquids, or semi-liquids, adapted to be connected to a carrier and provided with means to distribute the swill or other liquids as the container is moved along from place to place by the carrier, and it consists of an improvement in its construction to make it more convenient and effective, as hereafter described, and as particularly set forth in the claims.

In the accompanying drawings forming a part of this specification, Figure 1 is a perspective of a swill distributor embodying my invention. Fig. 2 is an enlarged section on line 2—2 of Fig. 1. Figs. 3 and 4 are enlarged detail perspectives.

Referring to the drawings, A is a container which is preferably made of sheet metal of cylindrical form. B is a bail connected to the container by ears E and provided with a chain C, or an equivalent device for attachment to an overhead carrier, not shown in the drawings. D represents a spout having an upwardly extended portion F on one end, said portion being adapted to fit against the bottom of the container. This flat portion is provided with an upwardly extending circular rib G, inside of which, near one side of the rib, is an opening H extending into the main opening I. A hole is cut in the bottom of the container near one side to admit and fit around the rib G, and the portion F is fastened to the bottom of the container by rivets, or otherwise.

J represents a circular shaped valve plate having a flat bottom adapted to fit on the flat part F' of the spout member inside of the rib G. It is also fitted with an opening K near one side adapted when placed in a certain position to correspond with the opening H in the face of the spout. A socket L is centrally located on the upper side of the plate J, into which the lower end of a rod M is inserted. The upper end of the rod

is pivotally supported by a bracket N attached to the adjacent upper edge of the container.

The upper end O of the rod M is bent at an angle to facilitate the rotating of the rod, whereby the openings H and K may be made to coincide to permit the outflow of the contents of the container, or be reversed to hold the contents in the container. To limit the rotation of the valve plate, I form a lug P on one of its edges which is adapted to contact with lugs Q on opposite sides of the rib G. In this way the valve will be rotated only about half way around, so as to either open or close the opening H in the spout as may be desired.

In the bottom of the socket L is a hole in which a bolt R is inserted and is passed down through a hole d in the flat portion of the spout member. On the extended projecting lower end of the bolt a compression coil spring S is mounted which is held in place by a nut, preferably double locked. By this means the valve plate, which should preferably be made of brass or a non-corrosive metal, is held in close contact with the flat portion F' of the spout member within the circular rib G, and when the opening H is closed there will be no leakage of the contents through the spout.

To provide more effectively for the distribution of the swill, or other contents in the container, I provide for an extension of the spout by a member which is lettered U, and which is pivoted to a lug or lugs V on the upper outer edge of the main spout member D. This extension of the spout may be held in operative position by a chain W, the upper end of which is held by a forked end on the outer end of the bracket N. By means of this extension spout the swill, or other contents in the container, may be conveyed some distance through the open spaces in animal pens into troughs or mangers located therein.

When it is desired to move in another place the extension spout may be folded up against the side of the container and be held in that position by looping the chain in the forked end of the bracket N. The dotted lines in Fig. 1 show the extension spout

raised and held in a position about half way up. The container is preferably fitted with two legs X, (one being on the opposite side), and the spout D answers in place of the 5 third leg to hold the container a distance above the ground or a floor when used in a building. In Fig. 2 Y represents an angle iron which is preferably used in constructing the lower portion of the container and 10 Z is a portion of the bottom of the container outside the rib G.

The valve arrangement is well calculated to handle swill or other liquid or semi-liquid ingredients, and the entire construction is 15 simple, inexpensive, durable and effective.

What I claim is:

1. In swill distributers, a container, a spout connected to and entering the bottom of the container, a rotatable valve on the 20 inner face of the spout, and a vertically disposed rod within the container having its lower end connected to the valve and its upper end extended to the upper edge of the container, whereby the valve may be 25 opened and closed by rotating the rod from its upper end.

2. In swill distributers, a container, a spout connected to and entering the bottom of the container, a rotatable valve on the 30 inner face of the spout, a vertically disposed rod within the container having its lower end connected to the valve and its upper end extended to the upper edge of the container, and a bracket attached to an upper 35 portion of the container to support the rod and permit its rotation to open and close the valve.

3. In swill distributers, a container, a spout connected to and entering the bottom 40 of the container, a rotatable valve on the inner face of the spout, a vertically disposed rod within the container having its lower end connected to the valve and its upper end extended to the upper edge of the 45 container, and a bracket attached to an upper portion of the container to support the rod, the upper end of the rod being bent at an angle to its body to facilitate the rotation of the rod to open and close the valve.

50 4. In a device of the character described, a container, a spout connected to the bottom thereof and having an opening into the container forming an outflow conduit, a valve plate adapted to cover and close the 55 opening in the spout, and having an opening in one of its sides corresponding with the opening in the spout and means to rotate the valve plate, whereby the outflow conduit in the spout will be closed and opened.

60 5. In a device of the character described, a container, a spout connected to the bottom thereof and having an opening into the container forming an outflow conduit, a circular rib on the face of the spout 65 rounding the opening and extending up into

the container, a valve plate fitting the face of the spout within the rib and having an opening corresponding with the opening in the spout, and means to rotate the valve plate, whereby the outflow conduit will be 70 closed and opened.

6. In a device of the character described, a container, a spout connected to the bottom thereof and having an opening into the container forming an outflow conduit, a 75 circular rib on the face of the spout surrounding the opening and extending up into the container, a valve plate fitting the face of the spout within the rib and having an opening corresponding with the opening 80 in the spout, a lug on one edge of the valve plate, a lug on each side of the rib, and means to rotate the valve plate and open and close the outflow conduit, the rotation of the valve plate being limited by the contact of the lug on the valve plate with the lugs on the sides of the rib.

7. In a device of the character described, a container, a spout member having a flat portion fastened to and extending into the 90 bottom of the container and having an opening therein forming an outflow conduit, a valve plate having an opening on one side corresponding with the outflow opening in the spout, and adapted to contact with and 95 be rotated on said flat portion of the spout, a bolt passed through a hole centrally located in the valve plate, and down through a hole in a rear portion of the spout, a compressing spring on the projecting end of 100 the bolt and means to secure the tension of the spring against the adjacent portion of the spout, whereby the valve plate will be held in close contact with the adjoining portion of the spout, to prevent leakage 105 when the outflow conduit is closed.

8. In a device of the character described, a container having a horizontally disposed bottom, a horizontally disposed spout rigidly secured to and extending below one edge of the bottom of the container, and downwardly projecting legs secured to opposite edges of the bottom of the container, whereby the container may be supported on a floor by means of the spout together with 110 the legs resting thereon.

9. In a device of the character described, a container having a horizontally disposed bottom, a horizontally disposed spout rigidly secured to one edge of the bottom of the container, an extension pivotally attached to an upper portion of the outer end of the spout, a flexible member having its lower end secured to an outer portion of the extension, and means on an upper portion of the container for adjustably supporting the upper end of the flexible member, whereby the extension may be raised and lowered on its pivot and be supported in various positions by the member.

10. In a device of the character described, a container having a horizontally disposed bottom, a horizontally disposed spout rigidly secured to one edge of the bottom 5 of the container, an extension pivotally attached to an upper portion of the outer end of the spout, a chain having its lower end secured to an outer portion of the extension,

and a forked bracket attached to an upper portion of the container, whereby the upper 10 end of the chain may be adjustably connected to the bracket and the pivoted extension may be supported thereby in different positions.

Fairfield, Iowa, November 26th, 1919.

ALBERT H. NELLER.
